UNITED STATES PATENT OFFICE

108,022

DESIGN FOR A TELEPHONE HAND-SET-MOUNTING

Hans Sengebusch, Villa Park, Ill., assignor to Associated Electric Laboratories, Inc., Chicago, Ill., a corporation of Delaware

Application June 12, 1937, Serial No. 69,815

Term of patent 14 years

To all whom it may concern:

Be it known that I, Hans Sengebusch, a citizen of the United States of America and a resident of Villa Park, Du Page County, Illinois, have invented a new, original, and ornamental Design for Telephone Hand-Set-Mounting, of which the following is a specification, reference being had to the accompanying drawings, forming a part thereof.

Fig. 1 is a front perspective view showing my new design of a telephone hand-set-mounting; Fig. 2 is a plan view of the hand-set-mounting; and Fig. 3 is a side elevational view of the hand-set-mounting.

I claim:

The ornamental design for a telephone hand-set-mounting as shown and described.

HANS SENGEBUSCH.
